BOTTLE STOPPER

Edgeworth Greene, Upper Montclair, N. J.

Application February 28, 1935, Serial No. 8,605
Renewed April 22, 1936

5 Claims. (Cl. 215—22)

This invention relates to stoppers or fitments for bottles or similar containers, and more particularly to stoppers or fitments for rendering such containers non-refillable.

5 Devices of this general character are illustrated in certain of my pending applications for patents, e. g., Serial No. 592,209, filed February 11, 1932, and Serial No. 735,950, filed July 19, 1934.

An object of the invention is to provide a stopper or fitment of the kind described, so constructed as to permit the dispensing of liquid from the bottle in a steady continuous stream without impairing the other functions of the device, and which, in particular, shall be effective 10 to prevent refilling; while at the same time it shall be largely proof against the accidents of shipping and assembly.

The novel features of the invention will be described fully in connection with the detailed description of the accompanying figures of drawing illustrating the preferred form of the invention, wherein:

Fig. 1 is a vertical section of a stopper embodying the invention and secured to the neck of a 25 bottle;

Fig. 2 is a section taken substantially on the line 2—2 of Fig. 1 and looking in the direction of the arrows of that figure;

Fig. 3 is a vertical section of the same stopper 30 showing the relation of parts when the bottle is held in inclined position with the mouth of the fitment open to a body of liquid, as when an attempt is made to refill; and

Fig. 4 is a perspective view of the inner or under face of the cover part of the stopper.

Referring to the drawing, 10 indicates the neck of a container such as a bottle having a top edge 11 and a bead 12 spaced from the top portion by groove 14. Secured to the bottle neck is a stopper 40 including a valve casing 15, preferably of thin sheet metal, a cover member 16 having a central orifice 17, and a gasket 18. Within the valve casing is suitable valve mechanism comprising a flat valve disc 19, a weighted valve member 20, and a 45 guard member 21. The stopper is secured in position by means of a ferrule 22, having a part 24 conforming to the shape of the top of the cover member 16, and having a skirt portion 25 spun into the groove 14 and over bead 12.

50 The interior longitudinal wall of the casing is provided with ribs 26, curved in cross section (Fig. 2), which form a number of channels 27 for the passage of liquid and air. These ribs terminate short of the upper end of the valve 55 casing, so that that upper portion is substantially truly cylindrical, in order that the cross section here may be maximum; in order that the upper end of the casing may receive the spacing and frictional lugs of cover 16 without necessity for 60 taking care to have the lugs out of alignment.

with channels 27; and in order to facilitate the formation of suspension flange 28, which is preferably annular as shown, extending laterally from and around the upper end of the casing 15. The ribs are so made as to minimize in pouring 5 the formation of films between them and the contained valve members, and as to provide passageways for liquid and air around the valve members. The lower end of the casing is formed into a bottom having a substantially central through 10 opening defined by an outwardly projecting tubule 30, such opening being surrounded at the inner end of the tubule by a flat valve seat 31 spaced from the wall of the casing and elevated relative to the lower extremity of the casing. 15 The elevation of the valve seat provides an annular trough around the seat 31 when viewed in the upright position of the bottle (Fig. 1). This formation has three important functions: First, by in effect isolating the valve seat from the adjacent walls of the casing it aids in preventing the formation of films which would dam or obstruct the free passage of air into the bottle in pouring and insures that no film having a short radius of curvature, and therefore high obstructive power, 20 25 can be formed adjacent the seat. Second, it enlarges the air space immediately adjacent the passage into the bottle, and by its form appears to materially promote the free flow of air therethrough by minimizing fluctuations of air pressure 30 at the point of ingress of air into the bottle. Third, the seat, being connected to the wall of the valve casing by means of a curved annulus, is reinforced by this annulus so that it can withstand, without deformation, considerable 35 pressure applied axially of the casing. Moreover, if the weight and/or guard member (hereinafter described) be made of porcelain or some other material which is relatively more frangible or deformable than is the valve seat, breakage or 40 deformation of these parts will occur before the valve seat has been mutilated to an extent sufficient to permit liquid to be forced into the bottle. Such breakage would interfere with the pouring clearance necessary for successful 45 operation. The curved annulus joining the valve seat to the wall of the valve casing also provides a passage 37 whereby liquid flowing into the valve casing through the tubule 30 may pass freely around the valve disc into the channels 50 provided by the ribs or flutes 26, and air entering from the exterior of the bottle may pass freely from the valve casing into the valve opening. The tubule 30 adds to the strength of the valve casing, and affords protection to the valve seat 55 against accidental injury such as might happen in shipping or assembling operations; and it has another function which will be described in connection with the description of operation of the valve parts.

The casing 15 including the flange and the bottom is advantageously made in one piece from some suitable thin metal, such as copper, which may be tin-plated to withstand the action of spirituous or other liquids. Copper is utilized as the base material, because it is cheap, workable, and sufficiently tough and rigid for the purposes of the structure in which it is embodied. And it is acceptable so far as concerns its effect on the bottled liquids for the protection of which the device is generally employed, e. g., whiskey, brandy, rum, etc., particularly when tin-plated. It is specially important that the valve seat be accurately formed, flat, and smooth. Therefore it is die-worked, and the piercing of the opening defined by the tubule 30, is from the interior of the shell outward, and so that the valve seat is free from adventitious inequalities of surface. I am thus able to secure a liquid-tight seal of the valve disc with the valve seat; and yet if slight vacuum develops in a tightly corked bottle because of cooling of the contained liquid, the vacuum is readily broken, upon opening of the valve chamber to atmosphere, by air passing between the smooth surface of the seat and the minutely irregular surfaces of the valve disc, these irregularities being too slight to permit liquid passage, however, under such trifling pressures. When greater pressures are used, as when an attempt is made to refill a bottle equipped with the fitment, the cork disc presses on the seat more tightly and seals the bottle. The metal of the valve casing is as stated of the minimum thickness commensurate with required rigidity and strength, for example a thickness of the order of 15/100ths of an inch or even less. The flange 28 as shown in the drawing, is of considerably less width than is the top 11 of the bottle neck.

It is also possible and may in some cases be preferred to form the under face of the cover member 16 with an appropriate annular depressed seat to receive the flange of the valve casing, the thickness of the flange in such case being preferably greater than the depth of the seat.

The valve disc 19 is made of some buoyant material, such as laminated cork or any other suitable material. This disc is of considerably smaller diameter than the diameter of the section determined by ribs 26, the latter being, as already noted, so formed that there is clearance sufficient to prevent the formation of films of small radius of curvature between them and the valve seat. This requires that the disc be capable of some considerable lateral movement relative to the longitudinal walls of the valve casing. The disc, however, must be of such diameter that it can preferably completely cover the valve seat 31, and certainly so that it can effectively close the inner end of the tubule 30 in even its most eccentric position relative to the tubule.

The disc is to be of minimum thickness compatible with other requisites and its edge curvature and clearance have a predetermined proper relation to the transverse curvature of ribs 26, such that likelihood of adventitious adhesion between the disc edge and the rib is minimized.

The weighted secondary member 20 is so constructed that the lowermost part thereof is substantially cylindrical, while the upper part is in the shape of a truncated cone. The bottom of this member is slightly dished or concaved as at 20', (Fig. 1), the concavity being bounded by a narrow flat edge portion or rim 20'', the flat surface of which that confronts the valve disc 19 being in a plane. The weight 20 is made

of some suitable material, such as, preferably, unglazed porcelain, glass, metal, etc. When the disc and the weight are wet and are brought into contact with each other in the presence of sufficient air, they will adhere to each other, a thin film of liquid forming between the flat rim 20'' and the disc 19, continuous with a slightly thicker film between the concavity 20' and the disc. However, if with the bottle inverted, the weight and disc are submerged sufficiently in liquid, the surface tension film between the weight and the valve disc is broken, the more readily and quickly because of the concavity at the bottom of the weight member, and the disc, due to its buoyancy, will float on the liquid and close the valve-opening 30. Matters of weight, areas of surfaces in operative contact, depth of concavity 20', etc. must be empirically determined so that in pouring, as the weight moves in a direction away from the valve seat, it will carry the valve disc along with it to permit liquid to issue from the interior of the bottle through the tubule 30 into the valve chamber. And it is necessary that the member 20 possess sufficient weight and adhesion-hold on the valve disc to overbalance the tendency of the valve disc to float when partially submerged, and to overcome the adhesion between the valve disc and the valve seat when the parts are in pouring position, so that movement of the member 20 away from the valve seat will cause simultaneous movement of the disc to uncover the valve opening for normal pouring. It is desirable also that the weight, once it has pulled the disc away from the valve seat, and carried it to valve-open position, shall maintain the disc in that position throughout the normal pouring operation, notwithstanding the forces exerted upon the disc and tending to re-seat it in the valve seat, as the result of the air which necessarily enters the valve chamber to compensate for discharged liquid.

The guard member 21 is preferably made of the same material as the member 20 but is of a diameter to fit fairly closely within the circle determined by the ribs 26. The bottom of the guard 21 is hollowed out in substantially cone fashion, with the walls of the cone formed into a plurality of ribs 21', whereby such contact between the outer surfaces of the conical part of the member 20 and the wall of the hollowed out portion of the guard as would result in adhesion between these two parts is prevented. Preferably, the guard is provided with a depending portion 32 contacting with the top of the member 20 and serving as a pivot about which the guard may rotate relative to the member 20. The top of the guard is recessed as shown, so that the side wall forms in effect an annular upstanding rib, whose inner wall preferably inclines outwardly away from the axis.

The cover member 16 may be made of any suitable material, such as porcelain, glass, metal, etc. Projecting from the bottom of the cover member adjacent the central orifice 17, is a number (three are shown) of integral lugs 34, uniformly spaced apart, and so dimensioned that a circle that includes the outer surfaces 34' of the lugs is slightly greater in diameter than the internal diameter of the upper cylindrical part of the valve casing, the surfaces 34' being beveled at their ends as shown at 34'', accordingly it is possible to enter the lugs into the valve casing, where they will be held by the friction of the surfaces 34' with the interior wall of the casing.

Thus, the parts can be assembled for handling with the valve mechanism retained within the valve casing, and breakage of the lugs is minimized because the lugs are quite wide as to the 5 surfaces that engage the casing wall, diminishing in width in the direction towards the orifice 17. In this connection it should be noted that the presence of the lugs in the upper end of the valve casing does not shut off liquid flow—first 10 because ribs 26 do not extend as far up in the casing as the bottom of the lugs, and second because of the generous spacing between lugs, their length, the fact that they are disposed about a relatively large discharge orifice 17, and the fact 15 that the spaces between lugs increase progressively from their inner surfaces 34'' towards their outer surfaces 34'. The lugs 34 also serve as stops limiting movement of the guard, weight and disc towards the cover member and away 20 from the valve seat. In the under surface of the cover member are a number of arcuate shaped grooves 35 extending between the respective lugs 34, the inner limits of these grooves being defined by upstanding rims 35' located in a plane 25 slightly below the plane of the flat gasket engaging surface 16' of the cover. (Fig. 4.)

The gasket 18 is made of some suitable material, such as cork, and as shown, it is wider than the flange 28 so that the top surface of the 30 gasket makes contact both with the bottom surface of the flange 28 and with the underside 16' of the cover member 16. When the gasket is compressed and the stopper locked in place, the gasket serves to make a liquid tight and airtight 35 seal between the top of the bottle and the cover member, and the valve casing, thereby preventing any leakage of liquid or entry of air.

A stopper made up as shown and described, when attached to a filled container of liquid, such 40 as a bottle, will serve to dispense the liquid and at the same time will oppose the introduction of other liquid into the bottle. The liquid may be dispensed by tilting the bottle to a not-too-steep angle, or pouring position. As the bottle is 45 moved to this pouring position, the weight and the disc will adhere to each other, and due to the physical weight of the member 20, the disc is carried by the latter away from the valve seat, permitting liquid from the bottle to enter the 50 casing, from which it flows through the central orifice in the cover member. When the bottle is restored to upright position, the disc is forced back into contact with the valve seat due to the action of gravity upon the weight and the 55 guard. In this upright position, liquid cannot enter the bottle since the valve disc is seated firmly on the valve seat; and if an attempt is made to force liquid into the bottle under pressure, the contact between the disc and the seat 60 is obviously undisturbed. If the bottle is inverted and air evacuated from it, liquid still cannot be forced vertically thereinto, since as the liquid rises in the valve casing the valve disc will float and move upwardly and seal the valve 65 opening.

An attempt might be made to refill a discharged bottle by exhausting the air from it and then holding it at a slight angle from the horizontal, as indicated in Fig. 3 (where 40 indicates the liquid to be introduced into the bottle 70 and where the weight is not effective to press the disc to closed position), reliance being placed on the proposition that if the liquid be now drawn in very slowly at this angle of the bottle 75 with respect to the outside liquid level, and the

relation of that level to the valve opening in the casing properly chosen and maintained, the liquid might find its way through the tubule without submerging the valve disc to the extent necessary to cause separation of disc from weight 5 and movement of disc to valve closing position. Fig. 3 illustrates what would happen under such conditions; i. e., as the relative liquid level rises, adhesion between the weight and the lower part 10 of the disc (that is, the part of the disc that is being increasingly submerged) is broken, the more promptly because of the presence of concavity 20'; as a result the lower part of the disc floats away from its adhesive engagement with the weight and contacts the lower arc of the valve 15 seat, while the upper portion of the disc remains in contact, hinge fashion, with the upper part of the weight edge, and would so remain if somehow the forces tending to move the disc towards the valve seat did not eventually overbalance the 20 slight adhesion of the upper portion of the disc to the weight. However, with proper proportioning of parts and relations of opposed adhesion surfaces of disc-and-weight and disc-and-valve seat, depth of concavity 20', size and weight of 25 disc, etc., one may insure that under all conditions such as those above indicated, the disc will close the valve opening before any liquid passes into the bottle. And here the tubule 30 comes 30 into play. Assuming the conditions of Fig. 3, 35 with a general liquid level as shown, there will be a local rise of liquid above that level, by capillary action, between the lower part of the disc and the confronting surface of the valve-seat, this raised body or film of liquid taking the form of a meniscus, indicated at 41. The pull of this meniscus may not suffice to move the disc to closing position, but as the general liquid level rises still further (so that, if the tubule 30 were not present, the liquid would pass through the valve opening), 40 the capillary meniscus rises still higher, while the flow of the body of the liquid is restrained by the upward inclination of the tubule (Fig. 3) and therefore the level of the main body of liquid also 45 rises in the valve chamber, decreasing the effective weight of the cork disc, so that the pull of the meniscus will presently draw the disc out of all contact with the weight and bring the disc to valve closing position, this hinge-like movement 50 of the disc being indicated by the arrow in Fig. 3, 55 and being facilitated by the fact that the disc is submerged to a greater portion of its height in the now deeper main body of liquid. All of this occurs very promptly, so that effective introduction of any but negligible quantity of liquid is 60 practically prevented. In my experience, with dimensions etc. as hereinafter set forth, I have found that the capillary or meniscus effect is pronounced when the maximum distance the disc 65 can move bodily away from the valve seat is not more than about $\frac{3}{2}$ ", where the shell 15 is of metal; and with this movability I obtain desirable maximum flow through the valve opening 70 into the casing in the normal pouring position of the bottle. If the shell is of porcelain, however, slightly greater movement may be allowed. 75

It will be obvious, referring to Fig. 3, that quick closing of the valve, under the operating conditions assumed, might be accomplished if the angles of the cone part of the weight and of the 70 cooperating guard surface were increased, so that the weight would slide out of the guard and carry the disc to closed position. However, such an expedient would have the result that for pouring the bottle would have to be tilted to a position de- 75

5	cededly nearer to the vertical, and therefore unnatural from the standpoint of the user, particularly where the guard and weight are of unglazed porcelain, with considerable coefficient of friction.	erally cylindrical valve casing provided at one end with an inlet and at the other end with a flat valve seat spaced from the side walls of the casing by an annular gutter and defining a valve-opening, a buoyant disc-like valve member having 5 one face confronting the valve opening, and of diameter substantially greater than the valve opening and less than that of the casing, said disc being movable towards and away from the valve seat, and a weight member movable within the 10 casing towards and away from the valve seat and having an end face adapted when wet to adhere to the other face of the disc, the movement of the weight member in the direction away from the valve seat being limited to permit maximum 15 flow of liquid through the valve opening into the casing in the normal pouring position of the bottle, and so that when, upon entrance of liquid into the casing through the inlet, the disc assumes a tilted position, with its lower edge portion submerged and in contact with an opposed part of the valve seat and its upper edge portion in contact with the end face of the weight member, there will be a capillary space between the disc and the valve seat, effective to cause local rise of liquid 20 above the general liquid level, whereby the upper part of the disc also is drawn into contact with the valve seat before the general liquid level rises sufficiently to cause flow through the valve 25 opening.
10	I have shown in the drawing an embodiment which has been found satisfactory commercially when applied to quart bottles of New England rum, ninety proof. In that embodiment, dimensions and weights are as follows:	2. The construction set forth in claim 1, in which the end face of the weight member confronting the disc is slightly dished.
10	Extreme internal diameter of shell 15 ----- $1\frac{1}{8}$ ''	3. The construction set forth in claim 1, in which the end face of the weight member confronting the disc is provided with a flat rim and a slight concavity bounded by the rim.
	Diameter of orifice 17 ----- $1\frac{5}{8}$ ''	4. The construction set forth in claim 1, in which the valve casing has an outward tubular extension whose bore coincides with the valve opening.
	Diameter of tubule bore ----- $1\frac{1}{16}$ ''	5. The construction set forth in claim 1, in which the end face of the weight member confronting the disc is slightly dished and in which the casing has an outward tubular extension whose bore coincides with the valve opening.
	Length of lugs 34 ----- $9/64$ ''	
15	Height of bead 35' above base of cover ----- $1\frac{1}{16}$ ''	
15	Clearance between top of guard and bottom of lugs (Fig. 1 position) ----- $5/64$ ''	
	Combined height of guard and weight (Fig. 1 position) ----- $1\frac{1}{32}$ ''	
20	Diameter of disc ----- $3/4$ ''	
	Thickness of disc ----- $1/8$ ''	
	Weight member 20, of porcelain.	
	Length of tubule ----- $7/64$ ''	
	Depth of grooves in cover, below rims 35' ----- $3\frac{1}{2}$ ''	
25	Width of grooves in cover ----- $13/64$ ''	
	Length of unribbed part of shell length ----- $1\frac{1}{4}$ ''	
	Angle of exterior of truncated portion of weight relative to axis ----- 30°	
	Angle of ribs interiorly of guard ----- 30°	
30	Minimum distance of valve seat from shell ribs ----- $7/64$ ''	
	Maximum depth of trough around valve seat ----- $3\frac{1}{2}$ ''	
	Dimensions of lugs:	
35	$1\frac{1}{16}$ '' at inner face, $1\frac{1}{4}$ '' on outer surface, $9/64$ '' long.	
	Maximum projection of ribs from shell wall .055''	
	Width of ribs, tapered to $3\frac{1}{2}$ '' radius at tip ----- $1/8$ ''	
40	Width of annular flat edge bounding the concavity 20' ----- $3\frac{1}{2}$ ''	
	Maximum depth of concavity 20':	
	Minimum ----- .005''	
	Maximum ----- .007''	
45	Maximum distance disc 19 can move away from valve seat ----- $3\frac{1}{2}$ ''	

I claim:

1. A protective bottle stopper including a gen-
